UNITED STATES PATENT OFFICE.

CHARLES HENRY GOODPASTURE, OF OLYMPIA, WASHINGTON.

AUTOMATIC TRAIN CONTROL.

1,116,055.

Specification of Letters Patent.

Patented Nov. 3, 1914.

Application filed February 11, 1914. Serial No. 818,042.

To all whom it may concern:

Be it known that I, CHARLES HENRY GOODPASTURE, a citizen of the United States, and a resident of Olympia, in the county of Thurston and State of Washington, have invented a new and Improved Automatic Train Control, of which the following is a full, clear, and exact description.

This invention relates to railway appliances and has particular reference to automatic means for preventing either front or rear head-on collisions on single tracks.

Among the objects of the invention more definitely stated is to provide a roadway with a continuous series of signals arranged in pairs, the signals of each pair being on opposite sides of the railway track and spaced at a distance equivalent to two blocks, the signals of the next pair being arranged to lap over or break joints with the preceding pair, whereby I provide a reliable interlocking block signal system.

A further object of the invention is to provide a means controlled by the setting of the signals for the automatic control of the running of the train, such control means being operative to stop a train coming in either direction, and thus preventing a block in which a train is running from being entered by another train.

The foregoing and other objects of the invention will hereinafter be more fully described and claimed and illustrated in the drawings forming a part of this specification in which like characters of reference indicate corresponding parts in all the views, and in which—

Figure 1 is a plan view indicating a series of blocks with associated signal and controlling devices; Fig. 2 is a vertical transverse section on the line 2—2 of Fig. 1; Fig. 3 is a vertical sectional detail on the line 3—3 of Fig. 1; Fig. 4 is a vertical sectional detail of a modified form of rail and actuating devices; and Fig. 5 is a longitudinal section on the line 5—5 of Fig. 3.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring more particularly to the drawings I show at 10 a single track roadbed having railway rails 11 of any usual or pre-

ferred form. Said roadway is arranged in a continuous series of blocks of any desired length, depending upon the number of trains to be provided for, said blocks being indicated in Fig. 1 at A, B, C and D.

At α I show a pair of signals of any suitable construction arranged on opposite sides of the railway track and spaced from each other a distance substantially equal to the length of two blocks. Said signal devices are shown herein as comprising a rotary disk 12 journaled in a casing 13 and adapted to rotate sufficiently far to show white or red according to the safe or danger condition of the track. A flexible connection 14 in the nature of a steel cable or the like extends from one signal α to the other, said cable being guided over any suitable number or arrangement of direction pulleys 15. Associated with the axle 16 of each signal disk is a drum 17 over which is extended the free end of the cable 14, said free end carrying a counterweight 18. The signal devices are substantially alike and hence a specific description and illustration of one will suffice for any number. At any suitable point in the cable 14 I provide a turnbuckle 19 whereby variations in length may be compensated for in a convenient manner.

An obstacle 20 of upright arrangement is mounted adjacent each signal station and is connected to the cable 14, and through the manipulation of said cable by any suitable means from the passing train the obstacle 20 is drawn toward the adjacent rail 11, as shown in full and dotted lines in Fig. 2, whereby, when the signal is set at danger the obstacle 20 will be close enough to the railway track to be in position to engage and trip any suitable form of air valve 21 carried on the right hand side of a locomotive, preferably close to the pilot.

As a convenient and reliable means for manipulating the cable 14 so as to set the signals and obstacles to danger positions by a passing train, I provide alongside of each rail an auxiliary or depressible rail or bar 22 adapted to be engaged and depressed by the first wheel of a train reaching a block to which said bar pertains, and said bar will be held depressed so long as any part of the train is within the two blocks along which each of said bars extends. In other words, the bar 22 extends from the signal station α at the approach of block A to the signal α adjacent the end of block B. When, there-

fore, a train enters block A the depression of the bar 22 on the right hand side thereof by the train will set both signals *a* to danger and the obstacles 20 associated therewith 5 will both be drawn toward the track rails. The signal at *b* guarding the block ahead of the train, however, remains clear until after the train has passed block A. The signal *a*, however, in advance of the train 10 protects such train from collision with the train approaching it from the other direction, the advance signal *a* being on the right hand side for such purpose. When the train enters block B the pair of signals *b* 15 will be set at danger by reason of the depression of the bar 22^b by a wheel on the left hand side of the train, the operation of the signals by the train being continued in the manner above set forth throughout the system. When the train enters block C the 20 first compressible bar 22^a will be released and the two signals *a* will be restored to normal or safety position by means of the counterweights 18, at the ends of the flexible connection 14. The signals *c* will be set and will remain in danger position until after the train has passed block D.

The means which I prefer to employ to cause the effective length of the cable 14 to 30 be shortened by action of the train comprises sets of pulleys 23 and 24 distributed in groups along the railway track at any desired distance apart. The pulleys 23 are arranged in pairs and support the cable 14 35 whether the cable is being acted upon or not by the compressible bar. The pulleys 24 are journaled upon the lower edges of the bars 22 and each of them acts between the two pulleys 23 of each pair, causing the 40 cable 14 to be deflected or looped, as indicated in dotted lines in Fig. 5. Such looping or bending of the cable 14 is sufficient to actuate the signal disks for the purposes above set forth and to set the obstacles into 45 tripping position.

From what has been stated above it will be understood that the obstacle 20 on the right hand side of the track which is set into tripping position by a train will move 50 into such position just after the valve 21 carried on or adjacent the engine pilot will have passed it. The obstacle 20 at the other end of the same cable 14 being on the opposite side of the track will have no influence 55 upon the train in question. The first mentioned obstacle, however, will be in position to stop an on-coming train should the engineer thereof disregard the signal intended for him to see. The obstacle 20, however, 60 at the forward end of the cable 14 will be

set to stop a train coming head-on toward the first mentioned train. It will be noted, therefore, that I provide a means insuring absolute safety to a running train at both the rear and the head, and under normal 65 running conditions such train will always have an open block ahead.

The auxiliary rail or compressible bar 22 is guided and kept in proper position by means of a guard plate 25 having a base 70 26 extending beneath the rail. Said guard is bolted at 27 to the side of the main rail, as indicated especially in Fig. 3.

The modification of Fig. 4 shows the rail 11' made in a peculiar manner so as to include the construction of the guard plate 25. For this purpose the rail is made with a cavity in which the bar 22 and the pulleys 23 and 24 operate.

Having thus described my invention, I 80 claim as new and desire to secure by Letters Patent:—

1. In a device of the character set forth, the combination with a railway track, of a pair of signals on opposite sides thereof and one being arranged in advance of the other, a cable extending along the track from one signal to the other, tension means applied to the ends of the cable serving to maintain the cable taut and the signals associated therewith in normal safety position, and means actuated by a passing train to bend the cable between the signals to shorten its effective length for the purpose of setting the signals at danger position against the 95 tension of said tension means.

2. In a device of the character set forth, the combination of a railway track having a pair of rails, of a pair of signal devices arranged on opposite sides of the track and one in advance of the other, a cable extending from one signal to the other along the track, tension means applied to the ends of the cable serving to keep the cable taut and the signals in normal safety position; a pair 100 of obstacles connected to the cable adjacent the several signals along the outside of the several rails, and means actuated by a passing train between the signals serving to set the signals at danger position and to move 105 the obstacles toward the rails against the tension of said tension means, substantially as set forth.

In testimony whereof I have signed my name to this specification in the presence 115 of two subscribing witnesses.

CHARLES HENRY GOODPASTURE.
